POCKETKNIFE

Boris Blecher, Philadelphia, Pa.

Application September 21, 1951, Serial No. 16,695

Term of patent 14 years

(Cl. D22—3)

To all whom it may concern:

Be it known that I, Boris Blecher, a citizen of the United States and a resident of Philadelphia, county of Philadelphia, State of Pennsylvania, have invented a new, original, and ornamental Design for a Pocketknife, of which the following is a specification, reference being had to the accompanying drawings, forming a part thereof, wherein:

The dominant features of my new design are shown in solid lines in the drawing.

I claim:

The ornamental design for a pocketknife, as shown and described.

BORIS BLECHER.
